INVENTOR.

Delmer D. Terrill,

BY *Geo. P. Kimmel*
ATTORNEY.

UNITED STATES PATENT OFFICE.

DELMER D. TERRILL, OF BANGOR, MAINE.

RAKER GAUGE.

Application filed May 16, 1927. Serial No. 191,774.

This invention relates to a device for dressing saws, more particularly to a gauge for use for jointing down rakers in a raker tooth saw, but it is to be understood that a 5 gauge, in accordance with this invention, can be employed for any purposes for which it is found applicable, and the invention has for its object, to provide in a manner as hereinafter set forth a raker gauge which is 10 simple in its construction and arrangement, strong, durable, compact, conveniently adjusted, thoroughly efficient in its use, readily assembled, providing for accurate adjustment, and comparatively inexpensive to 15 manufacture.

From the foregoing and other objects in view the invention consists, of the novel construction, combination and arrangement of parts as hereinafter more specifically described, and illustrated in the accompanying drawings, wherein is shown an embodiment of the invention, but it is to be understood that changes, variations and modifications can be resorted to which fall within the 25 scope of the claims hereunto appended.

In the drawings wherein like reference characters denote corresponding parts throughout the several views:—

Figure 1 is a side elevation of a raker 30 gauge, in accordance with this invention, and further showing the adaptation thereof with respect to the raker teeth of a saw.

Figure 2 is an inverted plan of the raker gauge.

Figure 3 is a top plan view of the raker 35 gauge.

Figure 4 is a cross sectional view thereof.

Figure 5 is a perspective view illustrating the guide plate and adjustable carrier there- 40 for.

Figure 6 is a longitudinal sectional view of the gauge.

Referring to the drawings in detail 1 indicates a body portion of polygonal contour and which has formed integral with the top, at the rear thereof, a head 2 which projects laterally, in both directions from the body portion 1. The front of the body portion 1 is formed with a vertically disposed groove 5' which extends from the bottom to the top of said body portion. The rear of the body portion 1 is provided with a vertically disposed oval-shaped slot 6 which opens into the groove 5'. The bottom of the body portion 1, at the rear there-

of is formed with a vertically disposed opening 7 having a threaded wall and which communicates with the oval-shaped opening 6.

The laterally projecting portions 3, 4 of the head 2 terminate in oppositely extending arms 8, 9, of appropriate length and which project above the upper faces of the lateral portions 3, 4 of the head 2. Each of said arms is formed with a pair of spaced vertically disposed openings 10 having threaded walls. The inner ends of the arms 8, 9 are positioned in opposed relation from and are spaced from the forward part of the body portion 1. The upper face of the head 2 is formed with a groove 11 disposed transversely thereof and the side walls of the groove 11 merge into the inner ends of the arms 8, 9.

Adjustably mounted within the groove 5 is a vertically movable carrier 12 of a length greater than the height of the body portion 1 and which is formed approximately centrally thereof with a transverse opening 13 having a threaded wall. The carrier 12 rides against the forward face of the head 2. The carrier 12 conforms in shape to the contour of the groove 5. Mounted upon the upper end of the carrier and projecting forwardly as well as from each side of the carrier 12 is a guide plate 13, of rectangular contour, and is formed in its forwardly projecting portion with a longitudinally extending slot 14 arranged forwardly of, but in close proximity to the carrier 12. In fact the rear side wall of the slot 14 is flush with the forward face of the carrier 12. See Figure 4. The slot 14 provides for the passage of the raker teeth 15, of a saw 16. See Figure 1.

Extending through the slot 6 and threadedly engaging with the wall of the opening 13 is a clamping screw 17 for maintaining the carrier 12 in adjusted position. The head of the clamping screw 17 abuts against the rear face of the body portion 1 when in clamping position. Engaging with the threaded wall of the opening 7 is a vertically disposed adjusting screw 18 which provides means for vertically adjusting the clamping screw 17, whereby the carrier 12 is adjusted with the screw 17, as it is carried thereby. The plate 13 is secured to the top of the carrier 12, by a holdfast device 19 which has threaded engagement with 110

the upper end of the carrier 12 and further has its head countersunk in the plate 13.

Mounted upon the arms 8, 9 are stop members 20, 21 for the saw teeth. The stop members 20, 21 are in the form of rectangular plates having the body portions thereof of less thickness than the thickness of the body portions of the arms 8, 9. The stop members 20, 21 project forwardly from the arms 8, 9 and are removably connected therewith by holdfast devices 22, which extend through slots 23 formed at the rear side edges of said stop members and engage the threaded walls of the openings 10. The stop members 20, 21 are of greater length than the length of the arms 8, 9, project from the inner ends thereof and overlap the guide plate 13.

The gauge is used for jointing down a raker or clearer tooth to the proper depth to suit the operator and can be used on any raker-tooth saw where raker is not too large to go through the slot 14 in the guide or filing plate 13. The stop members or plates 20, 21 bear on the groups of teeth at each side of the plate 13. The plate 13 can be elevated or lowered by the screws 17 and 18. Screw 17 is a set screw and screw 18 is an adjusting screw. The plate 14 is secured to the carrier 12. If the carrier with the plate 14 is to be lowered, screw 17 is loosened and screw 18 lowered, this releases the carrier and the latter can be pressed down to suit the operator. If the carrier is to be raised, screw 17 is loosened, and screw 18 turned in a direction to move upwardly to the height desired, screw 17 is then tightened and the gauge is ready for use.

It is thought the many advantages of a gauge, for the purpose set forth, owing to its simplicity and convenience in adjustment can be readily understood, and although the preferred embodiment of the invention is as illustrated and described, yet it is to be understood that changes in the details of construction can be had which fall within the scope of the invention as claimed.

What I claim is:

1. A gauge for the purpose set forth comprising a body portion having a groove in its front, a slot in its rear opening into said groove and an opening in its bottom communicating with said slot, an upwardly adjustable carrier mounted in said groove and carrying a forwardly projecting, slotted guide plate in its top, a head integral with the top of the body portion at the rear thereof, spaced oppositely extending arms connected to said head, forwardly projecting stop members carried by said arms and overlapping said plate, a clamping screw extending through said slot and threadedly engaging with said carrier, and means extending through said opening and threadedly engaging with the body portion for shift-

ing said screw to provide for the adjustment of said carrier.

2. A gauge for the purpose set forth comprising a body portion having a groove in its front, a slot in its rear opening into said groove and an opening in its bottom communicating with said slot, an upwardly adjustable carrier mounted in said groove and carrying a forwardly projecting, slotted guide plate in its top, a head integral with the top of the body portion at the rear thereof, spaced oppositely extending arms connected to said head, forwardly projecting stop members carried by said arms and overlapping said plate, a clamping screw extending through said slot and threadedly engaging with said carrier, and means extending through said opening and threadedly engaging with the body portion for shifting said screw to provide for the adjustment of said carrier, said head having its upper face provided with a transverse groove with the side walls thereof terminating in the inner ends of said arms.

3. A gauge for the purpose set forth comprising a body portion, an upwardly adjustable carrier mounted therein, a forwardly projecting slotted guide plate secured to the top of the carrier, a head arranged rearwardly of said plate and integral with the top of the body portion, spaced oppositely extending arms connected to said head, forwardly projecting stop members carried by said arms and overlapping said plate, and means carried by the body portion for adjusting the carrier and for clamping it in adjusted position.

4. A gauge for the purpose set forth comprising a body portion, an upwardly adjustable carrier mounted therein, a forwardly projecting slotted guide plate secured to the top of the carrier, a head arranged rearwardly of said plate and integral with the top of the body portion, spaced oppositely extending arms connected to said head, forwardly projecting stop members carried by said arms and overlapping said plate, means carried by the body portion for adjusting the carrier and for clamping it in adjusted position, and said head having its top formed with a transverse groove with the side walls thereof merging into the inner ends of said arms.

5. A gauge for the purpose set forth comprising a body portion, an upwardly adjustable carrier mounted in the forward part thereof, a forwardly projecting slotted guide plate secured to the upper end of the carrier, a head integral with the rear part of the body portion, at the top thereof, and extended laterally therefrom in both directions, oppositely disposed arms integral with the laterally extending portions of said head, means carried by said body portion for adjusting the carrier and for maintaining it in

adjusted position, and stop members projecting forwardly from said arms and overlapping said plate.

6. A gauge for the purpose set forth comprising a body portion, an upwardly adjustable carrier mounted in the forward part thereof, a forwardly projecting slotted guide plate secured to the upper end of the carrier, a head integral with the rear part of the body portion, at the top thereof, and extended laterally therefrom in both directions, oppositely disposed arms integral with

the laterally extending portions of said head, means carried by said body portion for adjusting the carrier and for maintaining it in adjusted position, and stop members projecting forwardly from said arms and overlapping said plate, said head having its top formed with a transverse groove and with the side walls of the groove merging into the inner ends of said arms.

In testimony whereof, I affix my signature hereto.

DELMER D. TERRILL.
